UNITED STATES PATENT OFFICE.

ANTON JULIUS GUSTAV EDWARD BERG, OF COPENHAGEN, DENMARK.

CYLINDER RELIEF-VALVE.

SPECIFICATION forming part of Letters Patent No. 730,085, dated June 2, 1903.

Application filed April 14, 1902. Serial No. 102,691. (No model.)

To all whom it may concern:

Be it known that I, ANTON JULIUS GUSTAV EDWARD BERG, a subject of Christian IX, King of Denmark, residing at Copenhagen, Denmark, (whose post-office address is Copenhagen, Denmark,) have invented a new and useful Improvement in Cylinder Relief-Valves, of which the following is a full, clear, and exact description, reference being had to the accompanying drawings, forming a part of this specification, in explaining its nature.

The invention relates to an automatic steam-trap for drawing the water of condensation from steam-cylinders.

In the drawings, Figure 1 is a view in elevation of my steam-trap. Fig. 2 is a vertical section thereof as shown in Fig. 1. Fig. 3 is a view in horizontal cross-section. Fig. 4 is a view on the line 4 4 of Fig. 5. Fig. 5 is a view in elevation of the valve and stem. Fig. 6 is a face view of the valve-head.

Referring to the drawings, A represents the casing of my device. It is formed, essentially, to provide the central chamber a , the two exterior chambered passages a' , and the connecting-ports a^2 . The exterior passages a' are of sufficient depth to permit of the movement of the reciprocating valves, of which I shall hereinafter make mention, and also to receive, respectively, the ends of the pipes B, connecting the two exterior passages, and so the chamber a , with the opposite ends of a steam-cylinder, that the water of condensation from either end of the cylinder may pass through the pipes B into and through the exterior passages to the central chamber, from which it escapes through its outlet a^3 . The pipes B make jointed connection with the casing by means of the couplings b, which screw upon the threaded end surfaces a^4 of the casing, and by their in-turned edges b', clamped against the flanges b'', formed on or attached to the ends of the pipes B, hold pipes and casing in tight connection.

Communication between the central chamber a and the exterior pipes and passages is closed by the valves C C', resting against their respective valve-seats c, cut in the interior wall of the casing at the entrance to

the ports a^2 . The valves are alike in their construction and are contained in that section of the exterior passages a' which comprises the valve-chambers c', of a width sufficient that an annular passage will be left between the valve-head and the wall of the chamber and of sufficient depth to permit of the reciprocation of the valve as it moves from a closed to an open position, the ends of the pipes B preventing any undue longitudinal movement.

The valves are so guided in their reciprocatory movement that when closed they may rest securely against their valve-seats by their valve-stems c'', extending between the guiding-walls of the parts a^2 and into the interior of the central chamber.

The valve-stems c'' have the hollow formation of a tube, and each receives the end sections of a spring C'', so compressed that it bears against the bottoms of the tubular stems with a tension sufficient to force the valves from their valve-seats. (See Fig. 2.) The normal position of the two valves is therefore open. Communication is then made possible between the valve-chamber c' and the central chamber a through the hollow interior of the valve-stems, for the ports a^2 are entirely closed by the valve-stems themselves. Inlet-passages c'' open from the valve-chambers into the interior of the valve-stems and the outlet-passages c'' open from the interior of the valve-stem into the central chamber. It is to be observed in this connection that the inlets c'' are cut into the valve-stem at a point which will provide an egress from the valve-chamber simultaneously with the opening of the valves, while the outlets c'' even when the valves are fully open still are in communication with the central chamber and its outlet a^3 .

As before explained, the exterior passages a' , which receive the ends of the pipes B, provide also the valve-chamber c, which contains the reciprocating valves. These valves if the tension of the spring which forces them from their valve-seats be sufficient, as is commonly the case with one when the other is closed, are thrown back against the ends of the pipes B, and so would close up their outlets.

This is provided for by the grooved recess c^5 , cut across the headed end surface of each valve and of a depth sufficient to insure a permanent communication between each pipe-5 outlet and the corresponding valve-chamber whatever the relation between the pipe ends and the valve-heads may be. When the valves are open, therefore, there is secured a continuous open passage from the pipes B 10 to the outlet a^3 , and in this connection it is to be observed that when one of the valves is held closed this has no effect upon the other valve except forcing it to a still wider opening by the increased tension upon the 15 connecting-spring. Upon the release of the closed valve it is forced back from its valve-seat by the tension of the spring, and both valves resume their normal open position. It is evident, therefore, that a valve can be 20 come closed only upon pressure against it sufficient to overcome the tension of the resisting-spring, and when this pressure is relieved the valve immediately is forced back to its normal open position whatever the position of the other valve may be.

The operation of my steam-trap is as follows: Assuming the pipes B to be in communication with the two corresponding ends of a cylinder the piston of which is at rest, no 25 steam being admitted into the cylinder, any accumulation of condensed water on either side of the piston would simultaneously pass off through the connecting-pipes B into the valve-chambers c' of the steam-trap. The valves C C' being open, for they are normally kept open by the tension of the spring C², the water would then flow through the inlet-passages c^3 into the interior of the valve-stems, through which it would pass, and then 30 out through the outlet-passages c^4 , or even the end of the valve-stem, into the central chamber a and to its outlet a^3 . Upon the admission of steam to the cylinder the valve in the steam-trap corresponding with the side 35 of the cylinder into which the steam has been admitted is immediately closed against its seat by the steam-pressure. This may be seen by reference to Fig. 3, where the valve C' is shown in closed position. This closing of the 40 valve prevents further passage of the steam and has no effect upon the other valve except possibly to force it to a still wider opening through increased tension upon the connecting-spring. The water of condensation then 45 passes off from the free end of the cylinder and, as before described, in case the valve-head has been forced back against the end of pipe B the passage of the water from the pipe into the valve-chamber is aided by the 50 grooved recess c^5 , cut across the head of the valve. Upon a reverse movement of the piston the pressure of steam in the other end of the cylinder simply occasions a reverse action of the steam-trap. The valve C on the 55 side of the steam-pressure is then closed, while the pressure upon the valve C' being

relieved it resumes its normal open position and the water of condensation passes off from that corresponding end of the cylinder. When the piston is at rest, therefore, the wa-70 ter of condensation will be let off from both sides of the piston; but when the piston is in motion the condensed water will then during further working of the engine be let off from one side of the piston at a time—namely, the 75 side opposite where the steam is entering the cylinder. It will therefore be impossible for condensed water to accumulate in the cylinder, and a uniform and noiseless working of the engine is insured, while at the same time, 80 the device being wholly automatic in its action, interruptions in the working are avoided.

Having thus fully described my invention, I claim and desire to secure by Letters Patent of the United States—

1. In relief-valves for steam-cylinders, the combination of a casing having a central chamber with an outlet, exterior passages leading to connect with the corresponding ends of a steam-cylinder, ports connecting 90 said passages with the said central chamber, outwardly-opening valves within said passages seated at the entrance to said ports and having stems passing through the walls thereof, which stems are of sufficient length to contact with each other within said central chamber and whereby one valve may be forced open as the other becomes closed, and yielding means for normally holding both valves open, but which permits of their alternate 100 closure by steam-pressure from the corresponding ends of the steam-cylinder.

2. In relief-valves of the character specified, the combination of a casing having a central chamber with an outlet, exterior pas-105 sages leading to connect with the corresponding ends of a steam-cylinder, ports connecting said passages with said central passages seated at the entrance to said ports and having stems passing through the walls thereof, 110 which stems are of sufficient length to contact with each other within said central chamber and whereby one valve may be forced open when the other becomes closed, and a tension-spring located between the said valves 115 for keeping both valves simultaneously pressed back to a normal open position, but which spring is of such tension that the valves may be alternately closed by steam-pressure from the corresponding ends of the steam-120 cylinder.

3. In relief-valves of the character specified, the combination of a casing having a central chamber with an outlet, exterior pas-125 sages leading to connect with the corresponding ends of a steam-cylinder, ports connecting said passages with the said central chamber, outwardly-opening valves within said passages seated at the entrance to said ports and having hollow stems passing through the 130 walls thereof, which stems are of sufficient length to contact at their ends with each

other within said central chamber and where-
by one valve may be forced open when the
other is closed, a tension-spring interposed
between said valves and contained within
5 their hollow stems, which spring normally
holds the valves open pressed back from their
valve-seats, but the tension of which is such

that the valves may become alternately closed,
substantially as described.

ANTON JULIUS GUSTAV EDWARD BERG.

In presence of—

JOHN JACQUES,
J. C. JACOBSEN.
